UNITED STATES PATENT OFFICE.

LESTER W. BERMOND, OF ST. PAUL, MINNESOTA, ASSIGNOR TO SWIFT & COMPANY, OF CHICAGO, ILLINOIS, A CORPORATION OF ILLINOIS.

BACON HANGER.

Application filed October 30, 1924. Serial No. 746,887.

To all whom it may concern:

Be it known that I, LESTER W. BERMOND, a citizen of the United States of America, and a resident of St. Paul, in the county of Ramsey and State of Minnesota, have invented a new and useful Improvement in Bacon Hangers, of which the following is a specification.

This invention relates to bacon hangers, used for supporting sides of bacon while being subjected to the smoking operation. The customary device for serving this purpose is a pronged support, the side of bacon being forced onto the prongs so that the latter penetrate the bacon along the flank edge. This piercing of the sides of bacon results in unnecessary waste which it is the purpose of the present invention to avoid. The waste is due to the necessity of rejecting the pierced portion of the bacon when it is sliced, and amounts to from three to six per cent of the sliced bacon. While the pierced portion of the bacon is, of course, fit for consumption, it is desired to have the highest grade product uniform and, therefore, the pierced slices cannot be marketed with the more uniform product.

The object of the invention is accomplished by means of a construction as illustrated in the drawing, in which:

Fig. 1 is a plan view of the improved bacon hanger.

Fig. 2 shows the device in transverse sectional elevation, being a section along the line 2—2 of Fig. 1.

Fig. 3 is a sectional detail taken on the line 3—3 of Fig. 1.

In order to effect the purpose of the invention, use is made of a pair of coacting serrated jaws, these jaws being arranged to slidably coact with one another in the gripping and releasing motions thereof. Each jaw is supported by a resilient wire arm, which arms are pivotally connected near their upper ends and one of which terminates with a bent hook by which the hangers may be supported on suitable conveyers. Pivotally connected to one of said arms and

embracing both is an operating lever which, by coacting with a curved corrugated surface of one of the arms serves to resiliently force it toward the remaining arm and thereby bring the jaws into gripping relation with the end of a side of bacon inserted between the jaws. This construction allows one jaw to be inclined away from the remaining jaw so as to compensate for the variation in thickness of bacon from side to side thereof. Each jaw is also arranged to incline upwardly toward the upper edge of bacon supported between the jaws in order that the weight of the meat will cause the serrations on the two jaws to grip the meat more tightly than would be the case if both jaws were to lie in substantially the same horizontal plane. The serrations or teeth on the jaws are, for the same purpose, bevelled toward their points along their lower edges.

The preferred construction as shown in the drawing comprises a pair of jaws 1 and 2, formed of strips of metal, the ends 3 of jaw 1 being bent inwardly to form a right angle with the serrated portion of the jaw between the bent ends. These ends 3 are slotted at 4 as shown in Fig. 2 for receiving the notched-out ends 5 of the jaw 2. By this arrangement the jaw 2 is maintained in transverse alinement with the jaw 1, but the loose connection afforded at slots 4 permit one end of jaw 2 to move into a position which is closer or farther away from the jaw 1 at one end than at the opposite end.

In this manner the device may compensate for variation in the thickness in a side of bacon from side to side thereof.

The supports 6 and 7 respectively for the jaws 1 and 2 are preferably formed from resilient material such as steel wire and are secured to the jaws at one end while being looped around one another at 8 (Fig. 2). The arm 6 extends above this pivotal connection, terminating in a hook 9 by which the device and a side of bacon thereon may be supported during the smoking operation.

The arm 6 is also looped at 10 to form a pivotal support for a clamping member 11.

This member is also preferably formed from wire suitably bent to embrace the arms 6 and 7 and twisted into a handle 12 at its free end. The arms 6 and 7 are bowed outwardly as indicated in Fig. 2 so that the jaws may be resiliently forced toward each other by a downward movement of the clamping member 11 around its pivot 10. The arm 7 is bent back and forth slightly to form the corrugations 13 between which the member 11 may be seated when the jaws 1 and 2 engage the side of bacon with the desired pressure. The teeth 14 on jaws 1 and 2 are in separate groups as shown in Fig. 1 and portions of the jaws are cut away at 15 between the sets of teeth in order to provide space within which the bacon may be crowded at the time of applying the device to a side of bacon. It is customary at such times to crowd the somewhat wider and thicker side of the bacon by means of a separate appliance, not shown, in order to keep the side of bacon, as much as possible, in a substantially rectangular form and compensate for 25 a difference in shrinkage between the heavier and lighter ends of the bacon during the smoking operation.

As shown in Fig. 2, the jaws 1 and 2 incline upwardly toward each other from a horizontal plane to cause the bacon to be held firmly gripped as a result of its own weight bearing down on the serrated jaws. Also for the purpose of more firmly gripping the bacon and only, at the most, making minute perforations therein, the teeth 14 are bevelled on their inner surface as indicated at 16 in Fig. 3. The jaws may, as indicated by dotted lines 2' in Fig. 1, incline toward each other at one end in a horizontal plane in order to compensate for variation in the thickness of the bacon in this direction.

In the operation of the device, it is applied to one end of the side of bacon, or the bacon is inserted between the jaws, while the latter is held more or less compressed in a desired rectangular form by separate means. When one end of the side of bacon is properly located between jaws 1 and 2, it is merely necessary to rock the clamp 11 downwardly around its pivot to cause the arms 6 and 7 and jaws carried thereby to be resiliently forced toward each other. The clamping member 11 is located in the desired position by being seated at the corrugations 13 in the arm 7 while the jaws 1 and 2 are uniformly urged toward each other throughout their entire lengths, one jaw inclining more or less toward the other, due to the resistance encountered and thereby compensating for the lateral variation in the thickness of the side of bacon.

While one preferred embodiment of the invention is herein illustrated, the device

might be modified in some respects without departing from the principal features of the invention upon which the claims are based.

I claim:

1. A bacon hanger comprising a pair of rigid jaws, the opposed edge of said jaws being serrated, a resilient support for each jaw, said supports being secured at the ends to their respective jaws and pivotally connected together at a point removed from said jaws, one of said supports being bowed away from the remaining support, and a clamping member adapted by coacting with said supports to draw one support toward the other. 75

2. A bacon hanger comprising a pair of rigid jaws, the opposed edge of said jaws being serrated, a resilient support for each jaw, said supports being secured at the ends to their respective jaws and pivotally connected together at a point removed from said jaws, one of said supports being bowed away from the remaining support, and a clamping member adapted by coacting with said supports to draw one support toward the other, one of said supports being corrugated or bent to form a plurality of seats for said clamping member. 80

3. A bacon hanger comprising a pair of rigid jaws, the opposed edge of said jaws being serrated, the serrations on said jaws being arranged in separate groups, said jaws being partly cut away between the groups of serrations, a resilient support for each jaw, said supports being secured at the ends to their respective jaws and pivotally connected together at a point removed from said jaws, one of said supports being bowed away from the remaining support, and a clamping member adapted by coacting with said supports to draw one support toward the other. 95

4. A bacon hanger comprising a pair of rigid jaws, the opposed edge of said jaws being serrated, said jaws being inclined with respect to a vertical plane passing between the same, a resilient support for each jaw, said supports being secured at the ends to their respective jaws and pivotally connected together at a point removed from said jaws, one of said supports being bowed away from the remaining support, and a clamping member adapted by coacting with said supports to draw one support toward the other. 100

5. A bacon hanger comprising a pair of rigid jaws, the opposed edge of said jaws being serrated, a resilient support for each jaw, said supports being secured at the ends to their respective jaws and pivotally connected together at a point removed from said jaws, one of said supports being bowed away from the remaining support, and a clamping member adapted by coacting with said supports to draw one support toward the other, one of said jaws having its ends 110

115

120

125

bent into coacting relation with the ends of the remaining jaw to provide a sliding connection between said jaws.

6. A bacon hanger comprising a pair of rigid jaws, the opposed edges of said jaws being serrated, each of said jaws having a support rigidly secured thereto, said supports being pivoted together at their outer ends and being bowed away from each other,

one of said supports being corrugated or bent to form a plurality of seats, and a clamping member embracing the corrugated support and having a hinged connection with the remaining support.

Signed at St. Joseph, Missouri, this 25th 15 day of October 1924.

LESTER W. BERMOND.
